UNITED STATES PATENT OFFICE

123,189

DESIGN FOR A COMBINED MIRROR, BRUSH, CONTAINERS, AND SUPPORT THEREFOR

Abraham Pavenick, New York, N. Y.

Application June 6, 1940, Serial No. 92,853

Term of patent 3½ years

To all whom it may concern:

Be it known that Abraham Pavenick, a citizen of the United States and resident of New York, in the county of New York and State of New York, has invented a new, original, and ornamental Design for a Combined Mirror, Brush, Containers, and Support Therefor, of which the following is a specification, reference being had to the accompanying drawing, forming part thereof, in which,

Fig. 1 is a perspective view of a combined mirror, brush, containers, and support therefor embodying my new design, and showing the mirror in open position; and

Fig. 2 is an enlarged front elevational view

thereof with the mirror in closed position.

The undisclosed top and bottom portions of the article are substantially plain.

The characteristic features of the design reside in the combination of the mirror, the support therefor, the brush and the pair of containers of the configuration substantially as shown, said brush and said containers being carried by said support and arranged as shown in Fig. 1.

I claim:

The ornamental design for a combined mirror, brush, containers, and support therefor, substantially as shown and described.

ABRAHAM PAVENICK.
